UNITED STATES PATENT OFFICE.

SAMUEL T. RUSSELL, OF SPRINGFIELD, OHIO.

PUMP.

SPECIFICATION forming part of Letters Patent No. 403,962, dated May 28, 1889.

Application filed November 30, 1887. Serial No. 256,575. (No model.)

To all whom it may concern:

Be it known that I, SAMUEL T. RUSSELL, a citizen of the United States, residing in Springfield, in the county of Clark and State of Ohio, have invented a new and useful Improvement in Pumps, of which the following is a specification.

My invention relates to improvements in pumps, and is applicable to the class known as "force" or "lift" pumps, which are usually constructed of metal.

My invention relates to means for inserting and securing the lining-cylinder within which the piston and valves of the pump are operated, and for other devices applied and used in combination, as will be hereinafter fully described in the specification, and more particularly pointed out in the claims.

Figure 1 is a vertical section of the barrel and operative parts of a pump having my improvements embodied therein. Fig. 2 is a top view of the pump-barrel, with the piston-rod, discharge-pipe, and brace-rod shown in cross-section. Fig. 3 is a cross-section of the pump-barrel near its lower end, and shows the centering-cleats in the bottom and the lining-cylinder or valve-chamber resting thereon.

The barrel A is cast in the usual cylindrical form, with a right-angled extension at the top for attaching the discharge-pipe H. The top end of the barrel is shouldered to receive a loose non-elastic ring, c, which is seated therein, sufficient space being left between the inner wall of this ring and the piston B to receive a leather gasket, f, of circular form, which extends also over the top of the ring and barrel under the cap C, which latter is held tightly thereon by bolts and nuts. The flange which forms the shoulder and seat for the loose ring c projects inward from the wall of barrel A nearly to the line of cylinder or valve-chamber b, allowing the latter, however, to be readily dropped down through it into the barrel.

The object in fitting the loose ring c into the top of the barrel on the flange or shoulder is to bridge over the space between the latter and the piston B, which is required to form a seat for the leather gasket f, and also by means of the removable ring c to provide

for the more ready removal of the operative parts of the pump in making repairs without the necessity of withdrawing it from the well. Below the flange on which the loose ring c rests is another flange, a, which projects inwardly far enough to form a vacuum-chamber, e, encircling the lining-cylinder b inside the barrel. This vacuum-chamber extends from flange a to the lower end of the barrel, 60 opening into the cavity under the cylinder where the induction-pipe enters the barrel. In the lower end of the barrel A are the three radial equidistant cleats d d d. These extend from the inner vertical wall of the barrel onto 65 the bottom toward the opening G. They are each about one-half inch thick, and their top surfaces incline inward and downward, so as to cause the lining-cylinder b to be adjusted centrally in the barrel at the lower end as it 70 rests upon them, leaving openings between the cleats under the end of the cylinder into the vacuum-chamber e. The lining-cylinder b is of brass or copper tubing, and is dropped into the barrel A until it rests on cleats d d d. 75 at the bottom.

The piston B is a closed cylinder of tubing with openings in the lower end. It is about one-half area of cylinder b, and is mounted upon the rod D, which latter extends through 80 it and has a large valve, F, on the lower end, fitting the chamber of cylinder b. A fixed valve, E, in the bottom of cylinder b rests on cleats d d d. This is provided with the usual bail used upon the fixed valves in 85 wooden pumps for convenience in removing it. The leather gasket f is pressed into shape before applying it, and forms a vertical packing collar or ring around the piston B, between it and the loose ring c, while its upper 90 horizontal flange extends outward over the ring c and the end of the barrel A, thus constituting a packing between the piston B and the ring c, between the ring c and the cap C, and also between the latter and the top end 95 of the barrel A.

I am aware that an inclined packing has been used, it having been forced or wedged in around the piston-cylinder by means of a cupped nut. This mode of packing is 100 seriously objectionable. When new the action of the water on the leather swells the latter

and causes the piston-cylinder to stick fast in the packing, and the cupped nut must be unscrewed and readjusted a number of times before it can be operated with ease. Besides 5 this, when the packing becomes worn and the cupped nut tightened down, the latter not unfrequently abrades the wall of the piston-cylinder. In my improved form of packing no attention is required to readjust the clamp-10 ing devices, and no danger of contact of the metal parts can happen however much it may be worn.

I claim as my invention—

1. In a force-pump, a barrel having two inwardly-projecting flanges at its upper end and radial self-centering cleats in its bottom end adapted to center and support a lining-cylinder and also to support a removable valve, in combination with said lining-cylinder and removable valve, a piston, a rod, D, a valve, F, a non-elastic removable ring seated on the uppermost of the flanges at the upper extremity of the barrel, a gasket formed to embrace the inner and upper sides of said 25 ring, and means for securing said gasket in position.

2. In a force-pump, a piston and a barrel having a flange at its upper extremity extending toward but not into contact with said 30 piston, in combination with a non-elastic ring removably seated on said flange, a gasket conforming in shape to the upper and inner sides of said ring, and having its skirt of substantially the same length as the thick-

ness of said ring, and adapted to be pressed 35 into contact with the piston-cylinder by the water in the barrel, and its top portion extending over upon the top of the barrel, a cap resting on said top portion of the gasket and having its outer edge substantially flush with 40 the outer edge of said top portion, and means for securing said cap in position.

3. In a force-pump, a piston, a valve, F, a rod, D, a barrel formed with a flange at its top extending toward but not into contact 45 with said piston, and also with radial self-centering cleats in its lower extremity adapted to serve both to center and support a lining-cylinder inserted within said barrel and also to support a removable valve, and the said 50 lining-cylinder and removable valve, in combination with a non-elastic ring removably seated on the flange at the top of the barrel, a gasket conforming in shape to the upper and inner sides of said ring, and having its 55 skirt of substantially the same length as the thickness of said ring, and adapted to be pressed into contact with the piston by the water in the barrel, a cap adapted to rest on the upper or horizontal portion of said gasket 60 and having its outer edge substantially flush with the outer edge thereof, and means for securing said cap in position.

SAMUEL T. RUSSELL.
